UNITED STATES PATENT OFFICE.

SIMON W. WARDWELL, OF PROVIDENCE, RHODE ISLAND.

BRAIDING-MACHINE.

1,081,474.

Specification of Letters Patent. Patented Dec. 16, 1913.

Application filed January 12, 1910. Serial No. 537,742.

To all whom it may concern:

Be it known that I, SIMON W. WARDWELL, a citizen of the United States, residing at Providence, in the county of Providence and State of Rhode Island, have invented certain new and useful Improvements in Braiding-Machines, of which the following is a specification.

My invention consists of improvements in braiding machines and relates particularly to that class of machines in which the yarn supplies are arranged in tiers and revolved in opposite directions about a common axis. In this style of braider the braiding operation is effected by deflecting the yarns from one set of supplies to cause them to follow a sinuous path in and out around the supplies of the other set.

The object of my improvement is to provide a machine of this character which will be capable of producing braid of varying patterns without the substitution of new parts.

The essential feature of the new machine comprises an adjustable, self-contained mechanism for controlling and regulating the deflection of the yarns so that their sinuous paths may be varied according to the pattern desired in the fabric.

My invention is fully described in the following specification, illustrated by the accompanying drawings, in which:

Figure 1 is a sectional elevation of the complete machine; Fig. 2, an enlarged sectional elevation of the central portion of the machine, taken on a plane at right angles to that of the section in Fig. 1; Fig. 3, a sectional view showing a detail of construction, taken on the line z—z of Fig. 4; Fig. 4, a plan view showing the switches for controlling the paths of the sinuating yarns, and illustrating their operating mechanism as employed for one variety of braid; Fig. 5, a similar plan view with the switches in a different position, and showing their operating mechanism for another variety of braid; Fig. 6, a diagrammatic representation of one variety of braid; Fig. 7, a development of the same, showing the relation of the fabricated yarns in this variety of braid; Fig. 8, a diagrammatic representation of another variety of braid; Fig. 9, a development of the same, showing the relation of the yarns in this style of braid; Fig. 10, a development of the exact pattern of plain braid, so-called; Fig. 11, a development

of the exact pattern of basket braid, so-called.

My new machine in general is similar in structure and arrangement to that described in my Patent No. 1,032,870, dated July 16, 1912. As shown in Fig. 1, it comprises a main frame 2, an outer turret 3, rotatable on balls 4 supported in a race on the frame 2; and an inner turret 5, carrying a head 6, 60 rotatable in a direction opposite to that of the turret 3 on the balls 7. A gear 8 fast on the shaft 9 and engaging gears 10 and 11 on the outer and inner turrets, respectively, serves to drive the latter in opposite 65 directions, as previously explained, when power is applied to the driving pulley 12. The clutch-mechanism for connecting the pulley 12 with the driving shaft 9, and the means for controlling the same to start or 70 stop the machine, are not here shown or described in detail as they form no part of the present invention. The outer turret 3 carries brackets 13 for supporting the yarn supplies 14, and suitable tension devices 15 75 mounted on the brackets are arranged to control the delivery of their individual yarns. In the outer rim of the turret 3 is a V-shaped, annular groove or race 16 in which travel the appropriately shaped runners 17 of the carriers 18. The carriers 18 support the upper set of yarn supplies 19 and are also provided with tension devices, 80 not here shown. Above each supply 14, and in line with the delivery point of its tension device, is a slit or thread-way 20 in the rim of the turret 3. These slits permit the lower 85 yarns α to play radially out and in as they sinuate over and under the carriers 18.

The carriers 18 are propelled to travel in 90 the race 16 by the oppositely rotating inner turret 5 through drivers 21 connecting them therewith. Two drivers are provided for each carrier, see Fig. 4, disposed in conico-radial guideways in the conical rim 22 of 95 the head 6. These guideways consist of slots formed in the upstanding portion 23 of the rim 22 and these slots are cut clear through the rim where the latter overhangs the rim of the turret 3. The drivers ride 100 on the edge of the dished portion 22 of the rim and on the outer flange 23^a formed on its periphery. A slight clearance is provided between the under sides of the drivers and the conical surface of the rim of the 105 turret 3 to avoid wear on these parts. In the surface of the rim of the turret 3 is a

cam groove 24 and the under side of each driver is provided with a stud or roll 25 which engages this groove. As the turret 3 rotates in a direction opposite to that of the head 6, which carries the drivers, the cam groove will act on the rolls 25 to project the drivers into and withdraw them from engagement with the carriers 18. The arrangement of the drivers with respect to the cam groove is such that each carrier is at all times engaged by one of its drivers and the drivers of each pair are withdrawn and returned into engagement with the carrier one after the other so that a passing yarn will encounter no obstruction in going between the carrier and the head 6. On the deck of each carrier are two abutments 26, see Fig. 4, having slots 27 with which the ends of the drivers engage. The drivers are held in position in their guideways in the head 6 by the conical rim 28 of a member 29. The member 29, which I term the bonnet, is of hat shape and at the top of its crown is mounted to rotate on a bearing 30. The bearing 30 forms a part of the tubular standard 31 which surmounts the frame 2 and is secured thereto by the screws 32. The outer rim 28 of the bonnet 29 is secured to the head 6 by screws 33, see Fig. 3, which also serve a further purpose as hereafter described. The bonnet 29 rotates as a part of the head 6 and serves as a hood or casing to cover and protect the internal parts of the machine. On the top of the bonnet is a conical cap 34 which incloses the mechanism for reciprocating the thimble or beater 35. This latter device acts to beat the yarns into the fabric and is described in detail in my application previously referred to, so that it need not here be further explained.

The yarns α from the lower set of supplies 14 and the yarns γ from the upper supplies 19 are led up to the beater 35 and converge in the tubular fabric at b . The braiding operation is effected by causing the sinuating yarns α to pass over certain carriers and under certain others as the supplies revolve in opposite directions. The deflection of the sinuating yarns is controlled by switches 36 which cooperate with the leading ends of the carriers 18. The carriers are formed with lenticularly shaped decks across the edges of which the yarns α draw and the supply packages 19 are surmounted with circular caps 37 which prevent the lower yarns from chafing on their edges. The leading ends of the carriers are pointed and the yarns α meet these points and are deflected either on to the outer edge of the carrier to pass above the supply 19, or on to the inner edge to pass under the latter. Normally, the mean radial positions of the lower yarns α would carry them inside the points of the carrier decks,

and to deflect them on to the outer edges the switches 36 are caused to take positions contiguous to the points of the carriers, as shown in Fig. 4.

In my application previously referred to 70 the switches for controlling the paths of the lower sinuating yarns are formed as triangular projections on a ring carried by the inner turret. This ring is oscillated in respect to the carriers to open and close the 75 slits between the carriers and their driving head. In my present machine I make the switches separate from the ring which actuates them and mount them on individual axes on the head 6. Preferably the switches 80 36 are pivoted on the screws 33. These screws extend through the rim 28 of the bonnet 29 and screw into the rim 22 of the head 6, see Fig. 3. To prevent the screws from binding the switches against the rim 28 they are formed with shoulders 38 which are set up against the face of the rim 22 and a slight clearance is provided under the heads of the screws so that the switches 85 turn easily on their pivots. The switches 90 36 are preferably made of sheet metal to render them light and thereby eliminate the effects of inertia and momentum in their action. As shown in Figs. 1 and 4, they are constructed with relatively long 95 arms 39 reaching out toward the points of the carriers 18 and arms 40, substantially perpendicular thereto, through which they are actuated. The end of the arm 39 is 100 bent down at 41 and terminates in a crescent shaped extension 42, adapted to overlap the point of the carrier deck and conforming to the shape of its outer edge.

For actuating the switches I provide a 105 ring 44 carried by and rotated with the inner turret 5 and adapted to be oscillated independently thereof. The ring 44 is mounted on flanged rolls 45 pivoted on the standards 46 extending upward from the base of the head 6, see Fig. 1. The rolls 45 provide for a practically frictionless bearing for the ring 44 on the head 6 and their flanges hold the ring from vertical movement. The ring 44 is connected to actuate the switches 36 by the following arrangement: On the periphery of the ring are projections or lugs 47, equal in number to the switches, and inclined upward so that they are just below the rim 28 of the bonnet 29 and in a plane parallel therewith. These projections are 110 formed with slots or openings 48 which engage pins 49 extending downward from the arms 40 of the switches 36. The pins 49 reach through suitable slots 50 in the rim 28 in which they are adapted to play, see Fig. 115 2. It will be seen that by oscillating the ring 44 with a rotary motion the switches may be actuated to throw their extremities 42 toward or away from the points of the carriers. The advantage of making the 120 125 130

switches separate from the ring 44 is that the latter may be made of considerable less diameter and is therefore much lighter. As the ring 44 must have a very rapid movement of oscillation this extreme lightness is important for lessening the effects of inertia and momentum, and thereby relieving the strain on the parts and providing for ease and smoothness of operation.

10 To actuate the ring 44 I make use of a lever 52 pivoted on a stud 53 screwed into the standard 54 on the head 6, see Figs. 1 and 2. One arm 55 of the lever 52 has an upwardly extending pin 56 which engages a hole in the rectangular block 57. The block 57 is fitted to a slot 58 on the ring 44 and when the lever 52 oscillates the block plays in this slot to provide for the divergence of the arcal path of the pin 56 from that of the ring 44. The lever 52 is actuated through its arm 59 by the novel interchangeable means now described.

15 In machines of this general arrangement heretofore used in the art the lever which oscillates the switches is actuated by a single cam secured to the central frame of the machine. With this arrangement when it is desired to braid a different pattern of fabric it is necessary to take the whole machine 20 apart and substitute a different style of cam for the one in place. It is obvious that such alteration in the machine will require considerable time and labor and it is my object in the present improvement to dispense with the necessity of taking down the machine 25 and substituting new mechanism. To attain this object I provide interchangeable cams built into the machine and adapted to be shifted at will, by a lever or other manually 30 operated means, to engage them successively 35 with the switch actuating lever 52.

40 Referring to Figs. 1 and 2, I have shown two cams 60 and 61 adapted to slide up and down on the central standard 31 of the machine frame. The cam 60 is preferably formed with a sleeve 62 bored to fit the standard 31 and turned down at 63 to receive the hub 64 of the other cam 61 which abuts the shoulder 65 to locate it thereon. 45 The cams 60 and 61 have grooves 66 and 67, respectively, in their opposed faces which are adapted to be engaged by the studs or rolls 68 and 69 on the lever 52. Figs. 1 and 50 2 illustrate the cams in their lowermost position with the roll 69 on the top of the lever 52 engaging the groove 67 in the upper cam 61. Fig. 4 is a plan view showing the roll 69 in this engagement with the cam 61 and 55 illustrates the form of the groove 67 by dotted lines. By raising the two cams on the standard 31 the upper cam 61 can be carried out of engagement with the roll 69 and the lower cam 60 brought into engagement with the roll 68 on the bottom of the lever 52. 60 Fig. 5 illustrates the roll 68 in engagement 65

with the lower cam 60, the upper cam 61 being removed to show the form of the cam groove 66. For shifting the cams I make use of a lever 70 pivoted at 71 on the overhanging portion 72 of the frame 2, see Fig. 1. A 70 rod 73 is bent at 74 to engage a hole at the inner end of the lever 70, see Fig. 2, and is secured in position by the pin 75. The rod 73 extends up through the central opening in the frame 2 and its upper end is bent at 75 right angles at 76 to project through a slot 77 in the standard 31. Driven into a transverse bore in the sleeve 62 is a hollow stud 78 which has its head 79 flattened on opposite sides to adapt it to fit the slot 77 in 80 which it slides, see Fig. 1. The end 76 of the rod 73 extends through the bore of the stud 78, and through a hole in the hub of the cam 61, and the pin 79 fastens it in place. This arrangement secures the cam 61 in 85 position on the sleeve 62 and the stud 78 sliding in the slot 77 acts as a key to prevent the cams from turning on the standard 31. By rocking the lever 70 the cams can be 90 raised or lowered on the standard 31 to successively engage the different cam grooves with their appropriate studs on the lever 52. To secure the cams in their operative positions I provide means for fastening the lever 70 at its outer end. This may be accomplished in any suitable manner and I have preferred to show a lug 80 on the portion 72 of the frame 2 having appropriately spaced holes for receiving a screw 81 extending through the end of the lever, see dotted lines, 95 Fig. 1.

100 The operation of the whole machine is as follows: The pulley 12, belted to a suitable source of power, turns the shaft 9, and through the gear 8 meshing with the gears 10 and 11 on the turrets 3 and 5, the latter are rotated in opposite directions. The lower supplies 14 are revolved on the turret 3 and their yarns *x*, drawing up to the braiding point *b*, move in the direction indicated by the arrow *a*, Figs. 4 and 5. The carriers 18, supported on the rim of the turret 3 with their runners sliding in the groove 16, revolve in the opposite direction to that of the supplies 14, as indicated by 110 the arrow *c*, Figs. 4 and 5. The carriers 18 are propelled by the turret 5 through the drivers 21 which reciprocate radially in alternately opposite directions to engage and disengage the grooves 27 in the abutments 115 on the carriers' decks. The drivers are actuated by the engagement of their rolls 25 with the cam groove 24 and their movement is so timed in relation to the movement of the lower supplies 14 that as the yarn *x* 120 enters the opening between the carrier and its driving head 6 the first driver of the pair will be withdrawn to let it pass by. After the yarn *x* passes the first driver the latter is shot back into engagement with the car- 125 130

rier and the second driver is then withdrawn to let the yarn pass out at this end. Normally the path of the yarn α will cause it to strike on the inner edge of the carrier's 5 point and with the switch 36 open, as shown in Fig. 5, the yarn will draw along this edge and be deflected to pass under the upper supply 19. When the switch is closed, as shown in Fig. 4, the yarn α will strike 10 against the crescent shaped extremity 42 and be deflected thereby on to the outer edge of the carrier deck to cause it to pass above the supply 19, see, also, Fig. 1. The switches are moved by the ring 44 which is oscillated 15 rotatively back and forth on the head 6 by the lever 52. The two cams 60 and 61 serve interchangeably to rock the lever 52 and both cams have grooves which give the same range of action to the lever and therefore to 20 the switches. In other words, either cam will operate to throw the switches the same distance from open to closed position, and vice versa. The essential difference between the two cams is in the timing of their movement of the switches. When the cam 61 is 25 in engagement with the lever 52 the movement of the switches is at relatively longer intervals and the timing is such that the switches will stay open while the yarns α pass by on the inside of two carriers. Likewise, when the switches are closed they will 30 stay closed until the yarns α pass by on the outside of two carriers. The result of this action on the fabric is shown in the pattern 35 of the braid. Fig. 6 illustrates diagrammatically the lower yarns α passing over and under the upper yarns y in pairs. This variety of braid is produced by the action of the cam 61 and it will be noted that while 40 any one of the lower yarns α is passing over two of the upper yarns y the next following yarn α will pass over only one of this pair of yarns y and under the next yarn y . In other words, each following yarn α splits 45 the pair of yarns y that the preceding yarn α has passed over and the same thing occurs in passing under the yarns y . Fig. 7 is a development of this character of fabric with the yarns shown spaced some distance apart 50 to make the pattern more plain. The crossing of the pairs of upper yarns y by the lower yarns α is progressive; that is, one yarn α' will pass under one pair of yarns y' and y^2 and over the next pair y^3 and y^4 , 55 while the next yarn α^2 will pass under only the yarn y' of the first pair and then over the yarn y^2 of this pair and also over the yarn y^3 of the second pair; then under the yarns y^4 and y^5 , and so on throughout the 60 whole fabric. This variety of fabric is called "plain" braid and its pattern is shown more correctly in Fig. 10 which is a development of the surface illustrating the yarns closely compacted. To make the illustration more 65 graphic the strands are shown as consisting

of three yarns each and the braid is generally fabricated with the strands in multiple as shown.

Figs. 8 and 9 are diagrammatic illustrations of the braid produced by the action of the lower cam 60. In this variety of fabric the lower yarn α' passes under one of the upper yarns y' , over the next yarn y^2 and under the next yarn y^3 . The next lower yarn α^2 passes over the yarn y' , under the 70 yarn y^2 and over the yarn y^3 . In other words, the lower yarns α pass over and under the upper yarns y singly and alternately. This variety of fabric is called "basket" 75 braid and its exact pattern is shown in Fig. 80 11 with the strands illustrated as composed of three strands each. It is obvious that the grooves in the cams 60 and 61 might be otherwise varied to produce still further 85 modifications in the pattern of the fabric, but the designs shown are those most frequently used.

From the above description it will be seen that my invention comprises a novel arrangement for producing different varieties 90 of fabric on the same machine. The interchangeable mechanism for actuating the switches is self-contained in the machine and may be set for the pattern desired by simply shifting a lever.

With my new device it is not necessary to 95 make any alterations in the structure of the machine and therefore time and labor is saved in changing from one variety of braid to another and the necessity of careful adjustment of parts is eliminated.

A further improvement in the construction of the machine is gained by making the switches which control the yarns separate 100 from the oscillating ring which operates them, so that the latter may be of less diameter than in my previous structure to provide for a minimum weight and lessen the effect of inertia and momentum.

Various modifications might be made in 110 the structure and arrangement of my new machine without departing from the spirit and scope of the invention, therefore, I do not limit myself to the precise form of construction shown, but

What I claim is:—

1. In a braiding machine, the combination with two sets of yarn supplies revolving in opposite directions, the yarns from one set sinuating through the supplies of the other set, of separate switches to control all of the sinuating yarns, a single member connected to each of the switches, and means to oscillate said member with a rotary movement about the axis of the machine.

2. In a braiding machine, the combination with two sets of yarn supplies revolving in opposite directions, the yarns from one set sinuating through the supplies of the other set, of separate switches to control all of the

100

105

115

120

125

130

sinuating yarns, a ring member connected to each of the switches, and means to oscillate said ring with a rotary movement about the axis of the machine.

5 3. In a braiding machine, the combination with a moving member supporting two sets of yarn supplies, of a second member moving adjacent the first in an opposite direction, means whereby one set of supplies is 70 propelled with and by the second member, a plurality of switches on the second member adapted to control the yarns passing by the supplies carried with said member, a ring carried on said second member and connected to each of the switches, and means to impart a rotary oscillating movement to the ring to shift the switches.

10 4. In a braiding machine, the combination with two sets of yarn supplies, of a moving member to carry one set of supplies, a second member moving in the opposite direction, means to move the other set of supplies by and with the second member, switches pivoted on the second member and 75 adapted to be shifted to control the braiding of the yarns, a ring carried by the second member and connected to each of the switches, and means to impart a rotary oscillating movement to the ring to shift the 80 switches.

15 5. In a braiding machine, the combination with a turret rotating in one direction and supporting two sets of yarn supplies, a second turret rotating in the opposite direction, drivers whereby one set of supplies is moved 85 in the same direction as the second turret, means on the first turret to actuate the drivers, switches pivoted on the second turret, a single member rotating with the second turret and connected to all of the switches, and means to oscillate said member with a rotary movement to shift the 90 switches.

20 6. In a braiding machine, the combination with two sets of yarn supplies, of a member to carry one set, a second member moving 95 in the opposite direction and arranged to drive the second set of supplies, switches on the second member adapted to be shifted to control the yarns, a member connected to 100 shift all of said switches and interchangeable means to actuate said member to shift the switches with differently timed movements to vary the pattern of the braid, said means interchangeable during the operation of the machine.

25 7. In a braiding machine, the combination with two sets of yarn supplies revolving in opposite directions, the yarns from one set 105 sinuating through the supplies of the other set, of switches revolving with one set of supplies and acting to control the sinuating yarns from the other set, and means interchangeable during the operation of the 110 machine to actuate the switches so that the

timing of their movements may be regulated to vary the pattern of the braid.

8. In a braiding machine, the combination with two sets of yarn supplies moving in opposite directions, the yarns from one set 70 sinuating through the supplies of the other set, of switches to control all of the sinuating yarns, means to actuate the switches with a predetermined timing of their movements and a second means for actuating the switches with a different timing of movement, with both of said means normally stationary in the machine but shiftable to render one or the other operative.

10 9. In a braiding machine, the combination with two sets of yarn supplies moving in opposite directions, the yarns from one set 75 sinuating through the supplies of the other set, of means to control the sinuating yarns, and interchangeable devices to operate said controlling means arranged to be shifted into or out of engagement with the latter during the operation of the machine to regulate the timing of the controlling means to 80 vary the pattern of the braid.

15 10. In a braiding machine, the combination with two sets of yarn supplies moving in opposite directions, of devices to cause the sinuation of the yarns from one set of supplies over and under the yarns of the other 85 set, and interchangeable means self-contained in the machine to operate said devices according to the pattern desired in the fabric, said means normally stationary in the machine but shiftable in position to render one or the other operative.

20 11. In a braiding machine, the combination with two sets of yarn supplies moving in opposite directions, the yarns from one set 90 sinuating through the supplies of the other set, of switches to control all of the sinuating yarns, means to actuate the switches, and interchangeable cams, self-contained in the machine, said cams shiftable into and out of position to operate the 100 switch actuating means.

25 12. In a braiding machine, the combination with two sets of yarn supplies moving in opposite directions, the yarns from one set 105 sinuating through the supplies of the other set, of means to control all of the sinuating yarns, and interchangeable cams, self-contained in the machine, said cams shiftable into and out of position to operate the 110 controlling means.

30 13. In a braiding machine, the combination with two sets of yarn supplies moving in opposite directions, the yarns from one set 115 sinuating through the supplies of the other set, of devices to control all of the sinuating yarns, interchangeable cams to operate said devices, and means to shift the cams to engage one or the other with the controlling devices.

35 14. In a braiding machine, the combina- 120

tion with two sets of yarn supplies moving in opposite directions, the yarns from one set sinuating through the supplies of the other set, switches to control the sinuating 5 yarns, means to shift the switches, a lever to operate said means, interchangeable cams to operate the lever and means to engage one or the other of the cams with the lever during the operation of the machine.

10 15. In a braiding machine, the combination with two sets of yarn supplies moving in opposite directions, the yarns from one set sinuating through the supplies of the other set, of switches to control the sinuating 15 yarns, means to shift said switches, a lever connected at one end to operate said means and carrying studs at its opposite end, cams formed with grooves adapted to engage said studs, and means to shift the 20 cams to carry one or the other into engagement with its respective stud on the lever.

16. In a braiding machine, the combination with two sets of yarn supplies moving in opposite directions, the yarns from one set sinuating through the supplies of the other set, of switches to control the sinuating 25 yarns, means to actuate said switches, a lever to operate said means, cams movable in and out of engagement with the lever, 30 and means to move the cams.

17. In a braiding machine, the combination with two sets of yarn supplies moving in opposite directions, the yarns from one set sinuating through the supplies of the other set, switches to control the sinuating 35 yarns, means to shift the switches, a lever to operate said means, cams movable in and out of engagement with said lever, devices to move the cams, and means to lock said 40 devices to secure the cams in their different positions.

18. In a braiding machine, the combination with a central stationary frame, of turrets rotating in bearings on the frame, two sets of yarn supplies revolved in opposite 45 directions by the turrets, means to interlace the yarns from one set of supplies with those of the other set, a lever to operate said means, cams movably mounted on the frame, 50 and means to shift the cams to engage either one with the lever.

19. In a braiding machine, the combination with a central stationary frame, of turrets rotating in bearings on the frame, two sets of yarn supplies revolved in opposite 55 directions by the turrets, means to interlace

the yarns from one set of supplies with those of the other set, a lever to operate said means, a bearing 31 on the machine frame, cams 60 and 61 slideable up and down on the bearing 60 and means to slide the cams to engage either one with the lever.

20. In a braiding machine, the combination with a stationary frame, of two sets of yarn supplies revoluble about the frame, 65 means to interlace the yarns from one set of supplies with those of the other set, interchangeable cams to control said means, said cams movably mounted on the frame, a lever pivoted on the frame and connected to 70 move the cams, and means to lock the lever to secure the cams in their different positions.

21. In a braiding machine, the combination with a central frame, of two sets of 75 yarn supplies revoluble about the frame, means to interlace the yarns from one set of supplies with those of the other set, a lever to operate said means, a tubular bearing 31 on the frame, a cam 60 having a sleeve slideable 80 on the bearing 31, a second cam mounted on said sleeve, a rod extending up through the bearing 31 and connected at one end with the cams, and a lever pivoted on the frame and connected with the opposite 85 end of the rod to shift the cams.

22. In a braiding machine, the combination with an outer and inner turret, of two sets of yarn supplies revolved in opposite directions by said turrets, switches on the 90 inner turret for controlling the yarns from one set of supplies, a plurality of roller bearings on the inner turret, a ring mounted on said bearings and connected with the switches, and means to oscillate the ring 95 with a rotary motion in respect to its turret.

23. In a braiding machine, the combination with two sets of yarn supplies moving in opposite directions, the yarns from one set sinuating through the supplies of the other set, of means to control the sinuating 100 yarns, a plurality of interchangeable non-rotatable cams self-contained in the machine, and means to connect one cam at a time with the yarn-controlling means to regulate the shifting of the yarns.

In testimony whereof I affix my signature in presence of two witnesses.

SIMON W. WARDWELL.

Witnesses:

DANIEL McNIVEN,
CHARLES D. REYNOLDS.
